UNITED STATES PATENT OFFICE.

ORVILLE C. HASKELL, OF CHICAGO, ILLINOIS.

CORSET-CLASP.

SPECIFICATION forming part of Letters Patent No. 225,520, dated March 16, 1880.

Application filed August 2, 1879.

To all whom it may concern:

Be it known that I, ORVILLE C. HASKELL, of Chicago, in the county of Cook and State of Illinois, have invented certain new and useful Improvements in Corset-Clasps; and I hereby declare the following to be a full, clear, and exact description thereof, which will enable others skilled in the art to which my invention appertains to construct and make use 5 of the same, reference being had to the accompanying drawings, in which—

Figure 1 is a front elevation of a corset embodying my improvement; Fig. 2, a view of one of the steels detached from the corset, showing 15 the fastening devices, and Fig. 3 the reverse side of the same; Figs. 4 and 5, detail views of the fastening or locking devices as they appear when ready to be attached to the corset-steels, and Fig. 6 a modification in the construction of the corset-steel.

The nature of this invention relates to an improvement in the means of fastening or securing corsets or corset-steels together in front; and it consists in certain novel features and arrangement of the parts, as will be hereinafter 25 more fully set forth in detail.

In referring to the drawings, A represents the corset-steels, (which are of the ordinary form of construction,) and B a fastening device, which is attached to one of the corset-steels, as shown in the drawings. b is a hook on the fastening device B, and is formed integral therewith.

C is a fastening device, composing one of 35 the locking members, and is of the form and construction shown in Fig. 5 of the drawings. This member C is attached to the opposite corset-steel from the one to which the members B are secured, and is provided with the shield a, all formed of one piece, and adapted for the reception of the hook b, thereby securing the parts together in the manner illustrated in Fig. 1 of the drawings.

The shield a not alone adds strength and 45 durability to the parts, but also prevents the wear and tear of the cloth covering the corset-steels and the up-and-down movement or play of the hook b when these parts are engaged.

50 The projecting points c of the locking members are turned at right angles thereto, as shown in Figs. 4 and 5 of the drawings, and, when attached to the steels, these points are bent downward, and are made to securely clasp the steels. These locking devices may also be

riveted to the steels, or attached in any other suitable manner.

It will be seen that this arrangement presents a very level and finished appearance to the corset, none of the locking parts showing 60 any uneven surfaces or projections that will inconvenience the wearer or destroy that portion of the clothing worn next to the corset.

One of the principal features in this improvement is the construction of the locking devices so that they engage with the outside edge 65 of the corset-steels. Thus the full strength of the material is obtained, and none of the parts can possibly give way under ordinary circumstances.

70 Fig. 6 represents a part of a corset-steel in a modified form, showing how the shield a might be dispensed with or have the shield set into the cut-out part of the steel, so as to come flush with the outer edge thereof, as represented at D.

I am aware of other devices attached to corset-steels for fastening the same; but many of 75 them are very objectionable on account of having projecting parts, which are very inconvenient and rapidly wear out the clothing, and lack the strength and durability so necessary in this class of goods.

In my improvement I aim to obviate these features in the manufacture of corsets, and at 80 the same time furnish a simple, convenient, and effective fastening device possessing great strength and durable qualities.

Having thus described my invention, what I 85 claim as new, and desire to secure by Letters Patent, is—

1. In a corset-clasp, the combination, with the corset-steels A, of the fastening device B, having the hook b, constructed integral therewith, and the locking device C, provided with 90 the shield a, adapted for the reception of the hook b, which engages with the same when the parts are locked together, substantially as described.

2. In a corset-clasp, the combination of the 100 following members: the corset-steels A, the fastening device B, the hook b, the device C, and the shield a, when constructed, combined, and arranged as herein shown, and for the purpose described.

ORVILLE C. HASKELL.
